DESIGN FOR A BABY CARRIAGE

James Michal, Chicago, Ill., assignor to Stork-line Furniture Corporation, Chicago, Ill.

Application January 21, 1936, Serial No. 60,706

Term of patent 3½ years

To all whom it may concern:

Be it known that I, James Michal, a citizen of the United States, residing at Chicago, in the county of Cook and State of Illinois, have invented a new, original, and ornamental Design for a Baby Carriage, of which the following is a specification, reference being had to the accompanying drawing in which Figures 1 and 2 are, respectively, front and rear perspective views of the article showing my new design.

I claim:—

The ornamental design for a baby carriage, as shown.

In testimony whereof I affix my signature.

JAMES MICHAL.
